LOOM SHUTTLE

Carl D. Brown, Hopedale, Mass., assignor to
Draper Corporation, Hopedale, Mass., a cor-
poration of Maine

Application July 1, 1936, Serial No. 88,438

1 Claim. (Cl. 139—223)

The present invention pertains to automatically threading loom shuttles, and has more particular reference to the threading devices of such shuttles.

5 Shuttles of this type comprise a shuttle body containing an automatically replaceable filling carrier, a side delivery eye, a threading block, having a horn, for guiding the filling into the delivery eye during the first two picks after transfer, and a thread engaging member cooperating with the horn to prevent the filling from escaping rearwardly about the horn instead of threading into the side delivery eye.

The principal object of the present invention 15 is to provide, in an automatically threading loom shuttle, having a shuttle body, threading block and horn as aforesaid, a novel and improved member for preventing the unthreading of the filling, which member shall be formed of a strip 20 of metal having one end secured to the shuttle by being inserted between the threading block and shuttle body.

A further object of the invention is to provide, 25 in an automatically threading loom shuttle having such shuttle body, threading block and horn, a member for preventing the unthreading of the filling, which member shall be formed of a strip 30 of metal bent into loops projecting to opposite sides of the horn as hereinafter claimed.

The aforementioned and other objects of the invention are accomplished by the construction illustrated on the accompanying drawing, of which:

35 Fig. 1 is a plan view of the thread delivery end of a shuttle having my invention applied thereto;

Fig. 2 is a longitudinal sectional view taken approximately on line 2—2 of Fig. 1, but to a 40 larger scale; and

Fig. 3 is a view in cross-section taken approximately on line 3—3 of Fig. 2.

The shuttle shown on the drawing comprises a shuttle body 1 having a longitudinal cavity 2 for 45 reception of a filling carrier, such as bobbin 3, and the threading instrumentalities hereinafter described in detail. The shuttle body is provided with any conventional means (not shown) for releasably holding the bobbin in the cavity and 50 permitting the bobbin to be automatically replaced by a fresh one whenever the filling supply becomes substantially exhausted.

The threading instrumentalities include a side 55 delivery eye 4 formed in the front wall of the shuttle in the usual manner, and a suitable

threading block for leading the filling into the side delivery eye during the first two picks after transfer. The threading block is fixed in a recess 5 in the shuttle body, and comprises a floor 6, front and rear walls 7 and 8, respectively, a scroll 9 and a horn 10 which projects outwardly and rearwardly from the front of the threading block. Threading blocks having these general characteristics are generally old.

The expressions denoting direction, as herein employed, are applicable to the shuttle when the latter is considered to be positioned in a loom and boxed at the side of the loom toward which the tip 11 of the shuttle points. Thus, "forwardly" is in a direction toward the front of the loom, and "outwardly" is in a direction from the cavity 2 toward the tip 11 of the shuttle.

The shuttle is provided with the usual longitudinal thread passage, which extends through the recess 5 and through the threading block. 20 A longitudinal groove 12 is formed in the shuttle body, the groove extending outwardly from the recess 5 substantially in alignment with the thread passage. The horn 10 is located above the thread passage and groove and preferably extends rearwardly to a point substantially in alignment with the rear wall 8 of the threading block. The rearward end of the horn is free and is turned downwardly at 13 into the groove 12. The shuttle is provided with a novel guard member for preventing the filling from unthreading rearwardly about the free end of the horn.

The guard member shown on the drawing is formed from a single rigid strip of material, preferably metal, bent to form oppositely projecting loops 14 and 15. The strip of metal may be rectangular in cross-section, and it is so shown on the drawing. The guard member is positioned entirely in the groove 12 and recess 5 beneath the horn, the member extending longitudinally of the shuttle approximately centrally of the groove. The loop 14 projects outwardly and the outer end of the strip is fixed in the groove by any suitable means, such as screw 16, while the opposite loop 15 projects inwardly beneath the horn into the recess 5. The loops, and the connecting portion of the guard member, are positioned in front of the down-turned end 13 of the horn, there being, however, space in the groove in front of the guard member to receive the running filling during the first pick after transfer. The loops extend materially above the down-turned end 13. The front surface of the guard member is, therefore, the thread engaging sur-

face which prevents the filling from escaping about the horn.

It is not broadly new to provide a guard member, for the purpose described, formed from a strip of metal attached to the shuttle body. However, the oppositely projecting loops, and more particularly the loop 15 which projects into the recess 5, are novel. I have also provided a novel means for firmly securing the guard member to the shuttle. As shown more clearly by Fig. 2, the inner end of the metal strip is bent downwardly at 11, to conform to the outer wall of the recess 5, and thence inwardly along the floor of the recess at 18, and is inserted between the bottom of the threading block and the shuttle body. Thus, the guard member is attached to the shuttle in such manner that it will not be dislodged by the shock and vibration incident to operation of the shuttle in a loom.

In the operation of the shuttle in a loom, a bobbin is transferred to the shuttle when the latter is boxed as above described. At such time, the filling end *f* extends from the bobbin outwardly and upwardly, over the threading block, to the usual fixed holder (not shown). Then the shuttle is moved bodily rearwardly and picked toward the left, Fig. 1. As the shuttle is thus picked, the filling in unwinding from the bobbin passes through the space about the down-turned end of the horn, upwardly between said end and the guard member, and thence to its running position in front of the guard member, wherein it is shown on Figs. 1 and 2. This threading of the filling occurs early in the first pick after transfer and the filling continues to run in this position throughout the remainder of the pick.

After the shuttle is boxed at the end of the

first pick, it is moved bodily forwardly and rearwardly and then picked in the opposite direction. Such movements of the shuttle slacken the filling and permit it to loop, twist and kink. The present form of the guard member is particularly efficient in preventing the thus slackened filling from escaping about the rearward free end of the horn. The filling being prevented from unthreading, it passes down into the side delivery eye during the second pick after transfer.

Having fully disclosed the preferred embodiment of my invention, I claim:

An automatically threading loom shuttle comprising a shuttle body having a cavity therein for reception of a filling carrier, a threading block fixed in a recess in said shuttle body, said threading block having a longitudinal thread passage and a horn which projects from the front of the threading block outwardly and rearwardly above said thread passage to a point substantially in alignment with the rearward side of the latter, the rearward end of said horn being turned downwardly into a longitudinal groove formed in said shuttle body, said groove extending outwardly from said recess substantially in alignment with said thread passage, and a guard member positioned entirely in said groove and recess, said member being comprised of a strip of metal bent into oppositely projecting loops one of which is fixed in said groove at a point outwardly from said horn and the other of which projects inwardly beneath said horn into said recess, said loops being positioned in front of and extending above said down-turned end of said horn, for the purpose described.

CARL D. BROWN.
